UNITED STATES PATENT OFFICE.

ROBERT AMOS BAGGETT, OF BELTON, TEXAS, ASSIGNOR TO MELLOR
BOX OPENER COMPANY, OF SEDALIA, MISSOURI, A COPARTNER-
SHIP.

COMBINATION-TOOL.

No. 12,458.

Specification of Reissued Letters Patent. Reissued Feb. 20, 1906.

Original No. 738,753, dated September 15, 1903. Application for reissue filed September 8, 1905. Serial No. 277,639.

To all whom it may concern:

Be it known that I, ROBERT AMOS BAGGETT, a citizen of the United States, residing at Belton, Bell county, Texas, have invented 5
a certain new and useful Improvement in
Combination-Tools, of which the following is
a full, clear, and exact description, such as
will enable others skilled in the art to which
it appertains to make and use the same, ref- 10
erence being had to the accompanying draw-
ings, forming part of this specification, in
which—

Figure 1 is a perspective view of the im-
proved implement. Fig. 2 is a view illus- 15
trating the manner of using the implement in
drawing large nails. Fig. 3 represents the
manner of employing the implement in draw-
ing small nails or tacks, and Figs. 4 and 5
illustrate the manner of employing the im- 20
plement as a wire-stretcher.

This invention relates to implements adapt-
ed for opening barrels, boxes, and similar
closures and which may also be employed for
stretching wires and driving or removing stapes
25 in constructing or repairing wire fences
and for other purposes, and has for its object
to simplify and improve devices of this char-
acter and increase the efficiency and usefulness
30 without increasing the weight or ex-
pense.

The invention consists in certain novel fea-
tures of construction, as hereinafter shown
and described, and specified in the claim.

The improved implement consists of a
35 stock or handle 10 of any approved length or
size, terminating in a chisel-point 11 in longi-
tudinal alinement with the handle and pref-
erably formed with a V-shaped cleft 12 to en-
able this portion of the implement to be em- 40
ployed for pulling tacks and small nails and
also to "start" the staples securing the wires
of fences and for other similar purposes.

Extending from one side of the handle 10
45 is a backwardly-curved portion 13, whose
rear end terminates in a claw portion 14, pro-
vided with a rearwardly-opening cleft 15, said
claw portion being adapted to be used as a
nail-puller and wire-stretcher, as shown in 50
Figs. 2, 4, and 5.

Extending from the handle 10 on the op-
posite side from the nail-claw member 13 is
a hammer face or lug 16 of any approved size.

With this implement many different kinds
of work may be performed. For instance,

the chisel end 11 may be driven between a 55
box-cover and the body of the box and the
back side of the claw 13 utilized as a fulcrum
to assist the operator in prying off the cover.

The chisel-point, with its cleft 12, will be
found very convenient in removing the "bar- 60
rel-linings" or "clime-hoops" in opening bar-
rels and removing the nails therefrom. The
chisel-point 11, with its cleft 12, will also be
found very convenient in drawing small nails 65
or tacks, the hammer-face serving as a ful-
crum when the implement is thus employed,
as shown in Fig. 3.

The claw member 13 will be found very ef-
ficient in drawing larger nails, and when thus
employed the chisel-point 11 serves as a ful- 70
crum to greatly increase the "draft" and pre-
vent the bending of the nails, as illustrated in
Fig. 2.

When employed as a barbed-wire stretcher,
the chisel-point will be placed against the 75
side of the post (indicated at 17 in Fig. 4)
and with the cleft 14 in the rear of the near-
est barb 18 on the wire 19. Then using the
implement as a lever the wire may be
stretched to any desired degree and secured 80
by staples in the usual manner, the peculiar
shape of the claw member 13 affording a bet-
ter grip for the nail or wire than the ordinary
claw.

When employed to stretch wire not having 85
barbs, the wire can be wound around the
hammer-face one or more turns after passing
through the cleft 14, as shown in Fig. 5, to
prevent slipping. Thus the implement can
be employed for a variety of purposes and all 90
the parts coact to produce the desired re-
sults.

The implement will preferably be con-
structed in one single piece of steel properly
tempered and may be of any desired size. 95

It will be found very convenient and effi-
cient for the purposes denoted and can be
manufactured very cheaply and of ample
strength to resist all strains to which it will be
subjected.

The implement will be found very conven-
ient for grocers and similar merchants and
also for farmers, fence-builders, and all me-
chanics who are called upon to perform rough
repair work.

Having thus described the invention, what
is claimed as new, and desired to be secured
by Letters Patent, is—

2

A tool comprising a stock having a wedge-shaped end extending in longitudinal alinement therewith, a claw member composed of a flattened arm extending laterally from one of the flattened faces of said wedge-shaped stock-terminal and spaced from the end thereof, said arm being curved rearwardly at a point intermediate of its ends with the free end thereof extended in a plane parallel with the plane occupied by the stock, said claw

member and wedge-shaped stock-terminal having V-shaped clefts therein opening in opposite directions; substantially as described.

In testimony whereof I hereunto affix my signature, in the presence of two witnesses, 15 this 4th day of September, 1905.

ROBERT AMOS BAGGETT
